Atty.

United States Patent Office.

G. E. HOYT, OF HEBRON, NEW HAMPSHIRE.

Letters Patent No. 97,511, dated December 7, 1869.

IMPROVED CLOTHES-DRYER AND STOVE-PIPE SHELF.

The Schedule referred to in these Letters Patent and making part of the same.

To all whom it may concern:

Be it known that I, G. E. HOYT, of Hebron, in the county of Grafton, and State of New Hampshire, have invented a new and useful Improvement in Clothes-Driers; and I do hereby declare that the following is a full and exact description of the same, reference being had to the accompanying drawings, and to the letters of reference marked thereon.

This invention relates to an improved clothes-drier, which is intended especially for use in connection with a stove-pipe. It is so constructed, however, that by the attachment of certain devices, it may be independently used, if desired.

Its novelty consists—

First, in the special construction of the supporting-ring which encircles the pipe, whereby it is made adjustable in size, and is rendered capable of receiving either rods for holding clothing, or a frame for supporting plates, &c., or both, as may be desired; and

Second, in the construction of the devices for making the supporting-ring capable of use independent of the stove-pipe, consisting of a tripod of ordinary construction, and a centre-piece having radial arms, by which the supporting-ring is held.

The details of construction and manner of operation will be fully described hereinafter.

In the drawings—

Figure 1 represents an inverted plan view of my invention;

Figure 2 represent a side elevation of the ring A; and

Figures 3 and 4, perspective views of parts detached.

To enable others skilled in the art to make and use my invention, I will now proceed to describe fully its construction and operation.

A represents the supporting-ring, which is constructed with the base a and flange a¹. This base and flange may be solid, if desired, (with the exceptions hereinafter mentioned,) or they may be constructed with ornamental openings, if preferred.

The ring thus formed of the base and flange, is in two parts, which parts are hinged together at a², and united, when in place, at a³, by means of a screw of any suitable construction.

In order that the ring may be used upon different sizes of stove-pipe, I provide it with the clamps B, which are constructed with the slotted foot-piece b, curving upright b¹, and projection b². These are held in place upon the base a by means of screws b³, which pass through the slot in the foot-piece.

By loosening the holding-screws b³, the clasps may be moved forward or back, as may be necessary.

The flange a¹ of the supporting-ring, is provided at regular and suitable intervals upon its base-line with square openings, as shown, into which is inserted, when desired, one end of the rods C.

These rods, thus inserted, are intended for holding

towels and other similar articles over and about the stove, for the purpose of drying them.

D represents a frame, constructed in two parts, which are hinged together, as shown at d d.

The larger of these two parts is constructed with one of its edges in a half circle, which fits accurately the outer circumference of the ring A.

It has also the arms d' d', which are so arranged as to correspond with two of the openings in the ring A.

When it is desired to use the frame for holding plates, &c., these arms are thrust into the openings at the centre of either half of the ring, the projecting ends of the frame being caught under the projections a⁴, upon the outside of the flange a¹, as shown in the drawings. In this position it is firmly held without other fastening.

To enable these devices to be used without connecting them to a stove-pipe, I provide a centre-piece, E, which is constructed with the socket e, bearing-flange e¹, and radial arms e². These arms are provided upon their upper side with a notch, e³, in which rests, when in position, the inner edge of the ring a.

F represents a tripod, of ordinary construction, by means of which the piece E is held.

To insert the piece E in place, the ring A is slightly opened.

From this description, the operation will be easily understood.

The ring A, when used in connection with a stove-pipe, is adjusted to suit the size, and is then fastened in place by means of the screw which unites the two parts.

The rods C are used entirely about the ring, if desired, or in connection with the frame D.

When used independently, the centre-piece is inserted and the tripod used. The device then may be moved from place to place at will.

Having thus fully described my invention,

What I claim as new, and desire to secure by Letters Patent, is—

1. The ring A, in combination with the centre-piece E, as and for the purpose described.

2. The specific device described, consisting of the ring A, clamps B, rods C, and frame D, when used in connection with a stove-pipe, as and for the purpose set forth.

3. The specific device described, consisting of the ring A, clamps B, rods C, frame D, and centre-piece E, when used in connection with a supporting-stand, as and for the purpose described.

This specification signed and witnessed, this 5th day of August, 1869.

G. E. HOYT.
